UNITED STATES PATENT OFFICE.

HARRY L. LISSFELT, OF NEW YORK, N. Y., ASSIGNOR TO MACBETH-EVANS GLASS COMPANY, OF CHARLEROI, PENNSYLVANIA, A CORPORATION OF PENNSYLVANIA.

DESIGN FOR A GLASS TUMBLER.

Application filed April 13, 1928. Serial No. 26,317. Term of patent 3½ years.

To all whom it may concern:

Be it known that I, HARRY L. LISSFELT, a citizen of the United States, residing at New York, in the county of New York and State of New York, have invented a new, original, and ornamental Design for a Glass Tumbler, of which the following is a specification, reference being had to the accompanying drawing, forming a part thereof.

The figure is a perspective side view of a glass tumbler, showing my new design.

I claim:

The ornamental design for a glass tumbler, as shown.

HARRY L. LISSFELT.
